C. L. NIEBERG, OF NEW HAVEN, CONNECTICUT, ASSIGNOR TO SARGENT & CO., OF SAME PLACE.

Design No. 2,586, dated February 19, 1867.

DESIGN FOR A COFFIN HANDLE.

The Schedule referred to in these Letters Patent and making part of the same.

TO ALL WHOM IT MAY CONCERN:

Be it known that I, C. L. NIEBERG, of New Haven, in the county of New Haven, and State of Connecticut, have invented a new Design for Coffin Handle; and I do hereby declare the following, when taken in connection with the accompanying drawing and the letters of reference marked thereon, to be a full, clear, and exact description of the same, and which said drawing constitutes part of this specification, and represents a front view.

The design which constitutes the subject of this application consists in the peculiar form and configuration of the handle and sockets.

C C are the sockets, and D the handle, formed so as to operate in the usual manner. The design is a socket, representing an acorn resting upon a branch of oak leaves; and the handle a vine formed from oak leaves, with acorns interspersed.

What I claim as my invention is—

The design for coffin handles, herein illustrated and described.
